UNITED STATES PATENT OFFICE.

MERRILL J. HELLER, OF LONGBEACH, CALIFORNIA.

DESIGN FOR AN EMBLEM.

No. 39,787.

Specification for Design.

Patented Jan. 26, 1909.

Application filed October 29, 1908. Serial No. 460,168. Term of patent 3½ years.

To all whom it may concern:

Be it known that I, MERRILL J. HELLER, a citizen of the United States, residing at Longbeach, in the county of Los Angeles and State of California, have invented a new, original, and ornamental Design for an Emblem, of which the following is a specification, reference being had to the accompanying drawing, forming part thereof.

The figure is a view in elevation of an emblem, showing my new design.

I claim:

The ornamental design for an emblem, as shown.

MERRILL J. HELLER.
